IGNITION SYSTEM

Ralph S. June, Seattle, Wash., assignor of one-half to George A. Anderson, Seattle, Wash.

Application June 25, 1934, Serial No. 732,288

6 Claims. (Cl. 123—148)

My invention relates to the ignition system of internal combustion engines. The invention is applicable admirably to the normal four-stroke cycle gasoline or explosion engine, having four cylinders or more, but its principles can be applied as well to such engines having two cylinders; to engines operating on the two-stroke cycle, and to semi-Diesel or Diesel engine; in fact, to any engine wherein an ignition system is used continuously or occasionally.

It is an object of my invention to simplify and lessen the cost of the ignition system of such engines, and to eliminate certain disadvantages inherent in the normal two-electrode spark plugs by providing a system wherein a one-electrode spark plug may be employed to advantage.

More specifically it is an object to provide an ignition system wherein a distributor is not needed, and wherein the timing is accomplished by the engine itself, that is to say, by the movement of the pistons therein, controllable by an auxiliary spark gap, in turn controllable in its initial setting and by the driver.

My invention comprises the novel ignition system, and the novel combination of the same with a multicylinder engine, by the latter term meaning an engine of two or more cylinders, preferably an engine in which the cylinders are arranged in pairs, the pistons in these paired cylinders approaching top center simultaneously, but being a half cycle different in phase, so that one piston is completing a compression stroke when the paired piston is completing a scavenging stroke. The invention, however, is not limited only to use in an engine so arranged, as will appear hereafter.

In the accompanying drawing I have shown my invention diagrammatically as incorporated in the normal four-cylinder, four-cycle gasoline engine, by way of illustration. The drawing shows such an engine in vertical axial section, with the electrical parts of the ignition system shown diagrammatically.

In such an engine, cylinders 1 and 4 are paired, as are 2 and 3. Pistons 10 and 40 in the respective cylinders 1 and 4 approach top center simultaneously, but are a half cycle opposite in phase, and similarly, pistons 20 and 30 are paired, but are a quarter cycle opposite pistons 10 and 40, and a half cycle opposite each other.

In each of such cylinders is secured a spark plug having a single electrode only. These spark plugs may be identical, but for purposes of description they are designated 11, 21, 31 and 41, to distinguish them, and are associated with the respective cylinders 1, 2, 3 and 4. These spark

plugs are supplied with continuous high-tension current from any suitable source, and as typical of such a source I have shown a vibrator coil 5 supplied with current from a battery 6. As is obvious, there may be substituted for such a current source any high-tension continuous generator.

Across the high-tension terminals 51 and 54 of this coil are connected the elements of a spark gap 7. These may consist of the adjustable spark terminal 74, adjustable by hand to regulate the initial spark gap, and the spark terminal 71 which is connected through a lever 70 and link 75 for adjustment by the driver or by any automatic governor device during operation of the engine, as is common for advancing or retarding the normal timing devices. A condenser 76 may be connected, if desired, across the spark gap 7.

Connecting the coil 5 and the respective spark plugs are the leads 12, 22, 32 and 42. The leads 12 and 42, of opposite potential, extend to the spark plugs 11 and 41, which are in the two cylinders of a pair, and the leads 22 and 32, of opposite potential, are similarly connected to the paired spark plugs 21 and 31, respectively.

If in the position of parts shown in the drawing we assume that cylinder 1 is under compression, the piston having just reached top center, then piston 40 has just completed a scavenging stroke. Piston 20 may have just completed a power stroke, and piston 30 an intake stroke. As piston 10 approaches its spark plug 11 on the compression stroke the resistance of the gap between this piston and spark plug diminishes, as does the resistance between the piston 40 and its spark plug 41, until the combined resistances at these two points become less than the resistance across the spark gap 7. When this occurs a spark passes by way of the lead 12, spark plug 11, piston 10, piston 40, spark plug 41, and lead 42, back to the coil 5. The gas in cylinder 1, being under compression, is fired by the spark thus passing, but since the piston 40 has just completed its scavenging stroke, no explosion can occur here, and consequently the explosion occurs only in cylinder 1. No spark can pass in cylinders 2 or 3, since the gap in these cylinders is so great.

As the cycle proceeds, the pistons 20 and 30 approach their respective spark plugs, and at about top center the spark passes in these two cylinders, firing the now compressed charge in cylinder 3, and thus the cycle continues.

It will be noted that the time of firing is determined by the time when the resistance between the two spark plugs of paired pistons be-

comes less than the resistance across the spark gap 7, and thus by controlling the spark gap 7, or by controlling the total resistance in this spark gap circuit, the time of firing can be controlled, and as one means of doing this I have shown the spark terminal 71 as adjustable, the opposite terminal 74 being manually adjustable to determine the initial resistance of the gap. By a proper adjustment of these spark terminals the engine may be made to fire earlier or later.

If this ignition system is connected in a two-cylinder engine, for instance an engine comprising only the cylinders 1 and 2, both spark plugs would be connected, as shown, to one terminal of the coil 5, and the opposite side of the coil will be grounded to the engine. Similarly, if the engine be a four-cylinder engine, or greater, operating on the two-cycle principle, all the spark plugs may be connected to one terminal of the spark coil, and the opposite terminal of the coil can be grounded to the engine. For a heavy duty engine, as in a truck, where a large spark is required, or for an engine of many cylinders (twelve or sixteen, for example), or for any engine operating at high speeds, or for any reason tending to overtax the capacity of a single coil, one coil may be employed for each pair of synchronously moving pistons, or for each group of four (or any convenient number of) cylinders, since there is no problem of synchronizing the timing of many spark plugs. In the claims, therefore, the term "current source" is to be understood as meaning one or more than one such source, as the type of engine may require. My system will, in fact, be particularly useful in engines wherein, because of high speeds, multiplicity of cylinders, or any other reason, timing or firing the charge is a problem, and the four-cylinder engine has been shown in the drawing only by way of illustrating, in the simplest manner, the principles of my invention, which, as indicated, will be especially useful in larger engines.

What I claim as my invention is:

1. In combination with a multi-cylinder engine and pistons reciprocable in the several cylinders, an ignition system therefor comprising a high tension current source; a one-electrode spark plug disposed in each cylinder to fire across to the piston therein substantially at top center of such piston, and leads from opposite terminals of said source to the spark plugs in those cylinders the pistons whereof are simultaneously at top center, but a half cycle opposite in phase, whereby the time of firing is controlled entirely by the approach of such pistons to their corresponding spark plugs.

2. An ignition system for use in engines of two or more cylinders comprising a continuous high tension current source, a one-electrode spark plug for disposition in each cylinder of two oppositely phased cylinders, to fire across to the piston there-

in substantially at top center of such piston, and leads from one terminal of said source to each of said spark plugs, the opposite terminal being electrically connected to the pistons, whereby the time of firing is controlled entirely by the approach of such pistons to their corresponding spark plugs.

5

3. In combination with a multi-cylinder engine and pistons reciprocable in the several cylinders, an ignition system therefor comprising a high tension current source, a one-electrode spark plug disposed in each cylinder to fire across to the piston therein substantially at top center of such piston, leads from opposite terminals of said source to the spark plugs in those cylinders the pistons whereof are simultaneously at top center, but a half cycle opposite in phase, and means adjustable to regulate the time of firing with respect to top center of such pistons.

4. In combination with a multi-cylinder engine and pistons reciprocable in the several cylinders, an ignition system therefor comprising a high tension current source, a one-electrode spark plug disposed in each cylinder to fire across to the piston therein substantially at top center of such piston, leads from opposite terminals of said source to the spark plugs in those cylinders the pistons whereof are simultaneously at top center, but a half cycle opposite in phase, and means controllable from a distant point to regulate the time of firing with respect to top center of such pistons.

5. In combination with a multi-cylinder engine and pistons reciprocable in the several cylinders, an ignition system therefor comprising a high tension current source, a one-electrode spark plug disposed in each cylinder to fire across to the piston therein substantially at top center of such piston, leads from opposite terminals of said source to the spark plugs in those cylinders the pistons whereof are simultaneously at top center, but a half cycle opposite in phase, and an adjustable spark gap connected across the terminals of said source, to regulate the time of firing with respect to top center of such pistons.

6. An ignition system for use in engines of four or more cylinders, wherein paired pistons simultaneously reach top center, but are a half cycle opposite in phase, comprising a source of continuous high tension current, a spark gap connected across the terminals of said source, a one-electrode spark plug for disposition in each cylinder, in position such that the paired pistons, substantially as they reach top center, will approach the respective electrodes closely to form gaps of combined resistance less than that of said spark gap, and leads from opposite terminals of said source direct to the respective spark plugs of paired pistons, whereby to effect a discharge within each of the paired cylinders.
